DESIGN FOR A TURNSTILE

Soren Madsen, Bergenfield, N. J.

Application February 12, 1938, Serial No. 75,103

Term of patent 3½ years

To all whom it may concern:

Be it known that I, Soren Madsen, a citizen of the United States, residing at 61 East Johnson Avenue, Bergenfield, county of Bergen and State of New Jersey, have invented a new, original, and ornamental Design for a Turnstile, of which the following is a specification, reference being had to the accompanying drawing, forming part thereof.

Fig. 1 is a front perspective view of a turnstile, showing my new design;

Fig. 2 is a side perspective view thereof; and
Fig. 3 is a top perspective view of the same.

I claim:

The ornamental design for a turnstile, substantially as shown.

SOREN MADSEN.
